UNITED STATES PATENT OFFICE.

JOHN S. KIDD, OF DES MOINES, IOWA.

WAGON DUMP AND ELEVATOR.

SPECIFICATION forming part of Letters Patent No. 447,191, dated February 24, 1891.

Application filed September 5, 1888. Renewed August 20, 1889. Again renewed August 11, 1890. Serial No. 361,640.
(No model.)

To all whom it may concern:

Be it known that I, JOHN S. KIDD, a citizen of the United States of America, and a resident of Des Moines, in the county of Polk and State 5 of Iowa, have invented an Improved Wagon Dump and Elevator, of which the following is a specification.

My object is to reduce the height of the platform upon which a wagon is drawn by 10 horses hitched to the wagon, as required, to favor the horses, and also to utilize the weight of the suspended elevator-box for raising the front end of a wagon preparatory to dumping its contents into the elevator-box.

15 My invention consists in the construction and combination of an adjustable section of a platform with a fixed section and an elevator-frame in such a manner that the adjustable section can be placed in an inclined position, 20 while a loaded wagon is upon it, and then moved longitudinally toward the elevator-box into which the contents of the wagon are to be dumped, and also in combining the elevator-box with the platform and the elevator-frame and hoisting mechanism in such a manner 25 that the weight of the elevator-box can be applied to the rear end of the adjustable section of the platform to raise the front end of a loaded wagon on the adjustable section.

30 Figure 1 of the accompanying drawings is a side view, and Fig. 2 a top view, of an elevator-frame and dumping-platform similar in construction and appearance to the frame and platform shown in my application, Serial 35 No. 284,307, filed August 31, 1888. Fig. 3 is a top view of the frame upon which the elevator-box is raised and lowered. Fig. 4 is a bottom view of an elevator-box adapted to be operated upon the frame. Fig. 5 is a side 40 view of a section of the frame that has bearings fixed thereto to engage the end of cross-bars fixed to the bottom of the box.

A represents the fixed portion of the wagon-platform, and A² the elevator-frame to which 45 it is attached.

B is the frame of the adjustable section of the wagon-platform, preferably supported at its front end upon wheels B³, that are con-

nected therewith by means of bearers B³, fixed to side bars of the frame. 50

C represents short rails or tracks fixed to the frame of the fixed portion of the platform in such a manner that the wheels B³ will travel thereon.

D are straight bars pivoted to the rear ends 55 of the side bars of the frame B, and also to the side bars at the base of the fixed portion A of the complete platform, in such a manner that they will swing vertically to aid in lifting the rear end of the adjustable section and 60 support it in an inclined position, as indicated by dotted lines in Fig. 1.

F is a shaft adapted to rotate in bearings fixed to the platform-frame A.

F' is a tubular shaft or sleeve on the shaft F. 65

F² are drums fixed on the ends of the shaft F, and F³ drums on the ends of the sleeve.

F⁴ is a clutch for connecting the sleeve with the shaft F so they will rotate jointly.

G is a rotating shaft in parallel position with 70 the shaft F. It has a fixed drum G² at one end, to which a rope G³ is fixed for operating the shaft.

H is a gear-wheel fixed to the other end of the shaft G to engage a wheel H², fixed to the 75 shaft F in such a manner that motion and power will be transmitted from one shaft to the other in raising and lowering the adjustable section B of the platform and an elevator-box.

J are ropes fixed to the rear and top corners 80 of the section B of the platform and extended over directing-pulleys J², attached to the elevator-frame, and from thence down to the drums F³, to which they are attached.

K is a frame suspended from the top of the elevator-frame by means of ropes K², that pass over directing-pulleys in a common way and are fastened to the drums F².

L are metal castings fixed to the frame, to 90 serve as corner-braces in the frame and also as bearings or fulcrums upon which to support and operate an elevator-box M, that has two bars N fixed across its bottom. The bars have journals N² on their ends, that fit and 95 operate on the fulcrums L in such a manner

that the box can be tilted in reverse ways at the will of the operator, as required to discharge the contents of the box in different directions at different times.

5 P is a ratchet-wheel on the end of the shaft G, and P² is a pawl pivoted to the platform-frame A in such a manner that any backlash of the hoisting-rope G³ will be prevented as the loaded box M is elevated, and also as required to retain the box elevated.

To place a loaded wagon upon the adjustable section B of the platform, an inclined approach is placed at the front end of said section, as indicated by dotted lines in Fig. 15 1, and the wagon then advanced over the approach to the top of the platform, by means of horses and by driving through under the elevator-box M, suspended over the approach. The approach is then removed and the pawl 20 P² adjusted to allow the shafts G and F to rotate and the box M to descend and rest upon the ground at the rear end of the platform-section B. As the box descends by force of gravity, the ropes K² unwind from the 25 drums F², and in so doing rotate the shaft F and wind the ropes J on the drums F³, as required to lift the rear end of the platform-section B and the front end of the wagon thereon. As the box descends and the wagon 30 and adjustable section are brought into an inclined position, they are also jointly advanced toward the elevator-box, as required to bring the end of the wagon-box in proper position to discharge its contents into the elevator-box. As the box descends, the horses 35 are backed and aid in tilting the dump-section and wagon. When the wagon is unloaded, the sleeve is freed from the shaft F by means of the clutch F⁴, to allow the sleeve 40 and drums on its ends to rotate and unwind the ropes J from the drums F³, as required to allow the elevated platform-section B to return to its normal level position, so that the wagon can be advanced and the hoisting-rope 45 G³ attached to the wagon and the loaded elevator-box hoisted as the wagon is moved from the platform.

By doubling the ropes J over the pulleys J² and connecting them with the drums F³ 50 and the movable end of the platform, and connecting the ropes K² with the drums F², of larger diameter, on the sleeve F', to which the drums F³ are fixed, the power of gravity inherent in the box is augmented sufficiently 55 to operate the platform-section in the manner described.

In my former application, hereinbefore referred to, I raise and lower an elevator-box by means of ropes passed over pulleys in the 60 same manner as now shown; but the ropes are not connected with the dumping-platform for the purpose of utilizing the weight of the box to lift the platform and dumping the wagon.

65 I am aware elevator-boxes have been suspended from the top of the frame, and con-

nected with mechanism on the platform and base of the frame by means of ropes for the purpose of raising and lowering the box; but my combination of an elevator-box with 70 a wagon-dumping platform and operating mechanism in such a manner that the weight of the box can be utilized to lift and dump a wagon is novel and greatly advantageous.

I claim as my invention—

75 1. In a wagon dump and elevator, the combination of a platform-section that is supported upon traction-wheels at one end and hinged to a fixed platform at its other end by means of straight bars in such a manner that 80 when the hinged end is elevated the complete section will be moved longitudinally toward an elevator-box, for the purposes stated.

2. The platform - section B, having fixed 85 bearings B² and wheels B³ at its front end and pivoted bars D at its rear end, in combination with a platform and elevator - frame and mechanism for lifting the rear end of the movable platform - section, for the purposes stated.

90 3. The ropes J, passed over pulleys J², attached to an elevator-frame, the rotating sleeve or shaft F', having fixed drums F³, and the platform - section B, supported upon wheels at its front end and connected at its rear end 95 with the fixed platform by means of bars D, arranged and combined to operate in the manner set forth.

4. The combination of the shaft G, having a fixed drum G³, and fixed gear-wheel H, the 100 shaft F, having fixed drums F³, the sleeve F, having fixed drums F³, the ropes J, extended over pulleys J², attached to the elevator-frame, the platform-section B, mounted on wheels at its front end and connected with 105 the fixed platform by means of bars D, and an elevator-box suspended from the top of the elevator-frame by means of ropes fixed to the drums F², to operate in the manner set forth, for the purposes stated.

110 5. A wagon dump and elevator comprising an elevator-frame and a wagon-platform fixed to the base of the elevator-frame, an adjustable platform-section supported upon traction-wheels at its front end, hinged to the 115 fixed platform at its rear ends by means of bars that allow vertical adjustment and longitudinal motion to the adjustable section, an elevator-box suspended from the top of the elevator-frame by means of ropes and pulleys, a rotating shaft having fixed drums to which said ropes are attached to raise and lower the said box, mechanism for rotating shaft, and ropes extended over pulleys attached to the elevator-frame and connected 125 with the shaft and also with the rear end of the adjustable platform section, arranged and combined to operate in the manner set forth, for the purposes stated.

130 6. In a wagon dump and elevator, the combination of a suspended elevator-box and adjustable platform-section and mechanism for

transferring the weight of the box to the said platform-section, for the purpose of elevating one end of a wagon on the platform-section.

7. The combination of an elevator-box suspended from the top of an elevator-frame by means of ropes, mechanism for operating the ropes to raise and lower the box, and an adjustable platform adapted to support a wagon

and connected with the rope-operating mechanism for the purpose of dumping the contents of the wagon into the elevator-box.

JOHN S. KIDD.
